UNITED STATES PATENT OFFICE.

GEORGE W. PIERCE, OF CAMBRIDGE, MASSACHUSETTS, ASSIGNOR TO MASSACHUSETTS WIRELESS EQUIPMENT COMPANY, OF BOSTON, MASSACHUSETTS, A CORPORATION OF NEW YORK.

RECTIFIER AND DETECTOR.

No. 879,117.

Specification of Letters Patent.

Patented Feb. 11, 1908.

Application filed April 5, 1907. Serial No. 366,568.

To all whom it may concern:

Be it known that I, GEORGE W. PIERCE, a citizen of the United States, and resident of Cambridge, Middlesex county, Massachusetts, have invented certain new and useful 5 Improvements in Rectifiers and Detectors, of which the following is a specification.

The invention relates to rectifiers and detectors for electric currents or electric oscillations and more particularly to rectifiers 10 and detectors such as may be successfully used as receivers in wireless telegraphy or electric wave signaling systems.

In practicing my invention I employ as a rectifier or detector a substance known as 15 hessite which occurs in nature usually as telluride of silver, although the silver is sometimes wholly or partially replaced by gold. I have discovered that this substance is asymmetrically conductive when used in 20 connection with small currents, and I have also discovered that by reason of this property of asymmetrical conductivity and possibly of other unknown properties this substance when properly placed between conductive electrodes is highly sensitive as a 25 receiver for electromagnetic waves.

The rectifying or detecting material may be utilized in many and various shapes and may be connected in the circuit of the 30 receiving or other apparatus in various ways.

For the purpose of illustration I have shown several forms of rectifiers and detectors in the accompanying drawings in which

Figures 1 to 3 show different ways in which 35 the rectifying or detecting material may be connected with electrodes. Fig. 4 shows a detector arranged in a direct connected receiving system, and Fig. 5 shows a detector arranged in an inductively coupled receiving 40 system.

In the arrangement of Fig. 1 a piece *a* of 45 hessite, is held in a clamp, the jaws *b* and *c* of which form electrodes making contact with the rectifying or detecting material.

I have secured the best results by cutting 50 a piece from a crystal on a plane substantially at right angles to its axis and engaging one of the electrodes with a point or corner of the crystal so that a small area of contact is secured.

In the arrangement of Fig. 2 a crystal or fragment of a crystal *d* is held in an ordinary

jewel mounting and a point of the crystal is engaged by a metallic spring *e*. The contact between the spring *e* and the detecting 55 material may be adjusted by a screw *f* to secure the character of contact which will give the best results.

In the arrangement shown in Fig. 3 a piece *g* of hessite is sealed in the end of a glass 60 tube *h*. The piece *g* is in contact with a mass of conducting liquid within the tube *h* and with a second mass of conducting liquid within a receptacle *i*, the masses of liquid forming the electrodes which contact with 65 the piece *g*. The liquid should be such that it will not act destructively upon the piece *g*.

Any other suitable form and arrangement of the electrodes and of the rectifying or detecting material may be employed which 70 may be found desirable or best suited to the conditions under which the particular apparatus in which the invention is embodied is to be used.

The constructions described or any other 75 suitable construction may be utilized to rectify small oscillatory currents wherever such rectification is desirable as for instance in investigating telephonic currents. These or other suitable construction may also be 80 utilized as wave detectors or receivers in any suitable or well known receiving apparatus for wireless telegraphy systems, and any suitable form of indicating device may be employed therewith such for instance as a 85 relay, a galvanometer, a telephonic receiver, a capillary electrometer, etc.

In Fig. 4 a receiver *j* embodying the invention is shown included in a direct connected receiving system, in which a telephonic receiver *k* is connected in shunt about the detector. A small battery *l* may be included in the indicator circuit although I have secured as good if not better results 95 without a battery.

When used the battery current lowers the resistance of the rectifier since the resistance of the rectifying material decreases with the increase of current, and by reason of the fact that the current through the detector is not 100 proportional to the voltage an additional rectification is obtained under some conditions.

In Fig. 4 a receiver *m* embodying the invention is shown included in an inductively 105

coupled receiving system. In this case the indicating device is shown as a galvanometer *n* connected in shunt about the receiver.

Other arrangements of circuits and other forms of indicating devices may be used with or without a battery in the indicator circuit according to the conditions under which the receiver is to be used.

What I claim is—

- 10 1. A rectifier for oscillatory currents consisting of a compound of silver and tellurium.
2. A rectifier for oscillatory currents consisting of crystalline telluride of silver.
3. A rectifier for oscillatory currents consisting of hessite.

4. A receiver for wireless telegraphy systems consisting of a compound of silver and tellurium in contact with two electrodes.

5. A rectifier for oscillatory currents consisting of hessite in contact with two electrodes.

6. A receiver for wireless telegraphy systems consisting of hessite in contact with two electrodes.

In witness whereof, I have hereunto set 25
my hand, this 19th day of March 1907.

GEORGE W. PIERCE.

In the presence of—

IRA L. FISH,

KATHARINE A. DUGAN.
